UNITED STATES PATENT OFFICE.

ALEXANDER M. WOOLFOLK, OF HELENA, MONTANA TERRITORY.

DEVICE FOR LOADING AND UNLOADING WAGONS.

SPECIFICATION forming part of Letters Patent No. 322,881, dated July 21, 1885.

Application filed March 2, 1885. (No model.)

To all whom it may concern:

Be it known that I, ALEXANDER M. WOOLFOLK, of Helena, in the Territory of Montana, have invented certain new and useful Improvements in Devices for Loading and Unloading Wagons; and I do hereby declare that the following is a full, clear, and exact description thereof, reference being had to the accompanying drawings, and to the letters of reference marked thereon, which form a part of this specification.

This invention relates to devices for loading and unloading wagons.

Its object is to generally improve and simplify the construction of devices of this character; and it consists in the matters herein-after described, and pointed out in the claims.

A loading device embodying my invention consists, essentially, of a wheel, which is pivotally connected with a wagon body or frame, so as to rest upon the ground, and which preferably forms one of the supporting-wheels of the wagon, said wheel being provided about its periphery with a series of receptacles or buckets arranged in such manner that each bucket, when brought near the ground or at the bottom of the wheel by the turning of the latter, will be in position to receive and hold material which may be placed within it, and when brought to the top of the wheel in the forward movement of the wagon will discharge into the wagon-body the material contained therein, the said wheel being preferably used in connection with a plow, scraper, or other similar device adapted to lift or scrape up from the ground and throw laterally into the receptacles or buckets the material to be loaded.

Any ordinary plow or scraper may obviously be used for the purpose last mentioned, and inasmuch as such plow or scraper may be detached and drawn separately from the wagon itself, and as the said buckets or receptacles may be filled by hand, or by other means than by such plow or scraper, without affecting the operation of the device so far as the lifting of material from the ground and depositing it in the wagon is concerned, a wheel provided with receptacles or buckets constructed to operate as above set forth is herein claimed without restriction to its combination with a plow or scraper. As advantageous results are, however, obtained by the use of a plow or scraper connected and moving with the wagon, and

supported therefrom in proper position to deliver material to the said receptacles or buckets, the said wheel is therefore also claimed herein in connection with such plow or scraper.

The invention also embraces features of construction in the wheel and in means for connecting a plow with the frame of a wagon, and also improved means for dumping material from a wagon, as will hereinafter appear.

In the accompanying drawings, Figure 1 is a side elevation of a device embodying my invention. Fig. 2 is a plan view of the same. Fig. 3 is a detail elevation of the lifting-wheel of the wagon. Fig. 4 is a transverse vertical section of the wagon, taken upon line *x x* of Fig. 2. Fig. 5 is a detail perspective view of a part of the rim of the lifting-wheel and one of the receptacles or buckets thereon. Fig. 6 is a detail fragmentary elevation of a part of the rim of the wheel viewed from the interior of the latter, one of the brackets being shown in section. Fig. 7 is a detail sectional view of a wheel generally similar to that shown in the previously-mentioned figures, showing the receptacles or buckets as arranged to discharge at the same side of the wheel as that at which they are filled. Fig. 8 is a detail perspective view of one of the buckets shown in Fig. 7.

In the said drawings, A is the wagon-body, B B' are rear supporting-wheels, and D D forward supporting-wheels therefor.

As herein shown, the rear supporting-wheel, B, at one side of the wagon is provided with receptacles or buckets C, for containing material to be lifted and deposited in the wagon-body, and a plow, E, is supported from the wagon-frame at one side of the said wheel with its mold-board toward the wheel, and in such position that the earth raised and turned over by the plow will be delivered into the said buckets.

As far as is concerned the general operation of the wheel B and buckets C in lifting from the ground and depositing in the wagon-body material placed in said buckets, the parts mentioned may be made in any manner found desirable and convenient; but in the device herein shown as one practical way of carrying out my invention the parts mentioned are made as follows:

The wheel B is preferably made of metal, and is provided with a relatively thin and broad tire or rim, B², having at its edge adjacent to the plow, or at the side of the wheel at

which the material is delivered, an outwardly-inclined, converging, or conical flange, B^3 , and at its opposite edge an inwardly-extending flange, B^4 . Both of said flanges are for the purpose of strengthening and making rigid the wheel-rim and for holding and delivering to the buckets C the material deposited upon the said rim, and the inclined or conical flange B^3 also for the purpose of facilitating the delivery to the buckets of the material cast upon it, as will hereinafter more fully appear.

As a desirable way of making the rim B^2 of the wheel with the flanges B^3 and B^4 , as described, the said rim is preferably formed by three separate annular parts or rings, b , b' , and b'' , of thin or sheet metal, preferably steel, the part b having upon it the flange B^3 , the part b' being of L shape in cross-section and having upon it the flange B^4 , and the part b'' being of the full width of the tread of the wheel and constituting an outer band or tire, which is placed around the inner portions of the rings b b' , which latter are preferably made to abut at their inner and adjacent edges, so that the main portion or body of the rim consists of two layers or thicknesses of metal and the flanges B^3 and B^4 of one thickness only. The rim B^2 is supported from a central hub, B^5 , by metal spokes, of which there are three sets, b^3 b^4 b^5 , which, as shown, are connected with the hub by being inserted in sockets or recesses in the latter, and are attached to the rim in a manner hereinafter described.

The wide wheel-rim B^2 preferably constitutes the outer walls of the several buckets C , which are preferably made of metal, and attached to or formed upon the said rim. In the particular construction of the parts herein shown, said buckets are made as follows: The buckets consist, generally, of side walls, C' and C'' , a back wall, C^3 , said walls being attached at their outer edges to the inner surface of the rim B^2 , and an inner wall, C^4 , uniting the edges of the walls C' , C'' , and C^3 , and forming the side of the bucket adjacent to the center of the wheel. The said several walls of the wheel-rim B^2 form a bucket open at its side, which is toward the rear of the wagon when the bucket is at the lower part of the wheel or adjacent to the ground, so that as the bucket rises in its backward movement relatively to the wheel-axle the open side or mouth of the bucket will come uppermost. The buckets are located at short distances apart upon the wheel-rim, and in the operation of the device all material thrown upon the said rim between the buckets and upon the conical flange B^3 will, when the rim assumes an inclined position in the rotation of the wheel, slide downwardly and into the said buckets. The sides C' of the buckets, which are adjacent to the conical flange B^3 , are preferably inclined from the mouth of the bucket inwardly from the said flange toward the rear wall, C^3 , of said buckets, as shown, and the said walls C'' of the buckets are made narrower than the front or open sides of the said buckets, so that trian-

gular spaces are left at the sides of the bucket within the said conical flange to receive the material which is thrown over the flange opposite the buckets, said material in the upward movement of the buckets obviously being caused to gravitate into the bucket at the rear of the one against which it is thrown.

In order to facilitate the discharge of the material from the buckets when the latter reach the top of the wheel, the inner walls, C^4 , of said buckets are inclined from the rear or back walls, C'' , inwardly toward the center of the wheel and the open sides or mouths of the buckets. The wheel also is provided with a series of laterally and inwardly inclined deflecting spouts or chutes, C^5 , herein shown as of curved form in cross-section, and as made integral with the edges of the inner walls, C^4 , of the said buckets, said deflecting plates or spouts being for the purpose of directing laterally into the wagon-body the material discharged from said buckets.

In the particular form of the device herein shown, the walls C' and C'' of the buckets are attached at their edges to the metal of the rim B^2 by means of angle-irons C^6 , secured to the metal of the rim and to the said walls C' and C'' of the buckets, preferably by means of rivets. The said wall C^2 of the bucket is conveniently riveted to the flange B^4 of the rim. Two of the spokes are preferably crossed, as shown, in order to brace the wheel laterally, and the buckets and the chutes C^5 are additionally supported by means of straps or clips embracing the spokes and riveted or bolted to the walls of said buckets and to the spouts, as shown.

As a preferable means of connecting the outer ends of the several spokes with the rim, the angle-irons C^6 are made of cast or malleable metal and are provided with lugs or projections $c' c'' c''$, located exterior to the walls of the buckets and provided with sockets or recesses for the spokes. The said lugs are preferably arranged one at each end of the angle-iron C^6 and the third at the apex of the angle or bend in said angle-iron, so that the outer ends of the several spokes $b^3 b^4 b^5$ are located adjacent to and outside of the walls of the buckets at three corners of the latter, as shown more clearly in Fig. 6. By this construction a simple and economical means is obtained for securing the spokes in place, and the latter are at the same time disposed in a manner calculated to support equally all parts of the rim without interfering with the walls of the buckets or with the entrance of material to and its exit from the latter.

The purpose of the flange B^4 of the wheel-rim is to retain upon the rim the material thrown upon it over the flange B^3 and to confine the said material so as to cause its proper delivery to the buckets.

As a convenient means of securing the spokes in the sockets of the hub and of the angle-irons C^6 , I preferably provide the adjacent faces of the spokes and sockets with re-

recesses or grooves, and after the parts have been placed together pour melted Babbitt or other readily fusible metal into the sockets, so as to fill all interstices about the ends of 5 the spokes, whereby the latter are held immovably in position.

When the wheel-rim is made of separate annular parts b , b' , and b'' , as before mentioned, said parts may be secured together by bolts or 10 rivets in any usual or preferred manner. In case, however, the buckets are made in the particular manner above set forth as affording a desirable way of constructing the latter, the said parts of the rim may be secured together by 15 the same rivets that are used to secure the angle-irons C^6 to the rim. When, also, the said angle-irons are provided with sockets for the attachment of the spokes, said angle-irons may be desirably provided at their sides adjacent to the lugs c , c' , and c'' with lugs c^3 , through which rivets are inserted for the purpose of more securely and rigidly holding the angle-irons in place.

In order to facilitate lateral movement into 25 the buckets of the material delivered upon the rim B^2 of the wheel, flanges or ribs C^7 are preferably located upon the inner surface of the rim, between each pair of buckets, said flanges being located at the side of the rim adjacent to 30 the conical flange B^3 and inclined inwardly toward the open sides of the buckets and terminating opposite the middle of the latter, so that in the downward sliding movement toward the buckets of the material upon the inner surface 35 of the rim said material will be deflected or carried inwardly and evenly disposed in said buckets, instead of accumulating at one side of the latter, as is apt to be the case in the absence of said flange or rib. The said ribs C^7 are 40 as herein shown, made of angle-iron and riveted to the metal of the rim, and are preferably extended at their outer ends over the surface of the flange B^3 , as shown, in order that the material thrown upon said flange B^3 may be 45 deflected inwardly by the outer end portions of said ribs for the purpose above stated. The angle-irons C^6 , uniting the bucket-walls with the wheel-rim, are also perfectly extended outwardly over the conical flange B^3 beyond the 50 edges of the buckets, so as to similarly deflect or guide inwardly to said buckets the material deposited upon the flange.

The wagon-body may be arranged in any suitable way in connection with the wheel B , 55 constructed as above described, in order that the material delivered from the buckets of said wheel may properly enter the said body. As herein shown, the said wheel B and the supporting-wheel B' are mounted upon the 60 opposite ends of an axle-tree, A' , extending across the wagon-body, and secured in longitudinal frame-pieces A^2 thereof. The side wall of the wagon-body adjacent to the said wheel B is preferably located close to the latter, and 65 A^3 , (shown in Figs. 1, 2, 4, and 7, and in dotted lines in Fig. 3,) which is inclined upwardly

and outwardly, and the upper edge of which is extended beneath the lower edges of the inclined chutes C^5 upon the buckets, so that the 70 material which passes from the buckets when the latter are inverted upon reaching the top of the wheel will fall upon the said shield and will be deflected thereby into the wagon-body.

As a desirable way of supporting the plow 75 E in a desired position with relation to the wheel B , and of making the necessary draft-connections between the plow and the wagon-frame, means are herein provided as follows: The plow E is provided with the usual beam 80 E' , and with upwardly-extending pieces or arms E^2 at its rear end corresponding in position with the handles customarily employed. The said plow is connected at the forward end of the beam E' and at the upper ends of the 85 arms E^2 with a longitudinally-arranged and forwardly and downwardly inclined frame, F , which is located outside of the wheel B above the plow, and is supported at its rear end by a cross-piece, G , forming a part of the frame 90 of the wagon, and at its forward lower end by a chain, H , adjustably connected at its upper end with the wagon-body. The frame F is pivotally connected with the cross-piece G , and the chain H is connected with the wagon 95 by means adapted to permit the front end of the said frame to be adjusted vertically, the adjusting device herein shown consisting of a pivoted hand-lever, H' , connected at its lower end by means of a rock-shaft, H^3 , with 100 a horizontally-arranged arm, H^2 , to the free end of which the upper end of the chain H is attached, said lever H' being provided with a spring-detent engaging a notched segment, H^4 , upon the wagon-body, whereby the lever may 105 be held so as to support the forward end of the frame in any position desired.

The plow-beam being connected at both ends with the frame F , it is obvious that when the said frame is moved vertically the entire 110 plow will be raised or lowered. In order, however, to enable the plow-point to be raised or lowered, as desired, when the plow is moved bodily, as above described, means are provided for adjusting the rear end of the plow 115 vertically with reference to the frame E , the devices herein shown as used for this purpose being constructed as follows: The frame F is provided with a vertical standard, F' , to which is pivoted a horizontally-arranged hand-lever, 120 F^2 , with its forward end at a point near the driver's seat, and having its rear end pivotally connected with arms E^2 at the rear end of the plow, preferably through the medium of a rock-shaft, F^3 , pivoted upon the frame, and 125 provided with an arm, F^4 , connected with the lever F^2 , by means of a pivoted bar, F^6 , and with two arms, F^5 , connected at their free ends with the arms E^2 of the plow by means of pivoted connecting-bars F^7 .

The object of the construction embracing the rock-shaft F^3 and arms F^4 and F^5 is to afford a more rigid connection between the rear end of the plow and the frame F than would 130

exist in case the arms E^2 of the plow were connected with the lever F^2 without the interposition of said rock-shaft.

Any suitable means may be used for adjustably holding the rear end of the plow when the latter is moved vertically by the means above described, that herein shown consisting of a notched segment, F^8 , upon the standard F' , which is engaged by a spring-detent upon the lever F^2 .

The connecting-bars F' are desirably each provided in their lower portions with a series of bolt-apertures f , and the said bars are connected with the arms E^2 of the plow by bolts $15 f'$, which may be placed in either of said apertures, as desired, and the rear end of the plow thereby adjusted vertically to a greater extent than can be conveniently accomplished by the movement of the lever F^2 alone.

20 By the construction above set forth it is obvious that by the use of the levers H' and F^2 the plow can be bodily raised and lowered, as desired, and that the plow may be placed at such angle or in position with its point raised 25 or lowered relatively to the main portion thereof as may be found necessary in the operation of the device.

The frame F may be constructed in any desired or preferred manner; but, as herein 30 shown, said frame consists of two longitudinal bars, $f^2 f^2$, Figs. 2 and 4, suitably connected by cross-pieces, and pivoted at their rear ends to lugs g upon the cross-piece G , the outer bar at the front end of the frame being united 35 with the inner bar by means of a metal cross-piece, g' , as shown.

The forward end of the plow-beam E' may be provided with the usual clevis E^3 , and connected with the frame F by means of a link, e , 40 engaged with a rod or bolt, f^3 , supported at its ends in the side pieces, f^2 , of the said frame.

The bolt e' , connecting the link e with the clevis, may obviously be shifted into one or another of the apertures of the latter, and the 45 front end of the plow-beam thereby adjusted vertically with reference to the frame.

The plow E is located at such distance from the wheel, as may be readily determined by experiment, that the earth lifted by the share 50 and turned over by the mold-board will fall upon the wheel-rim and will be thereby carried into the buckets, as above set forth.

The presence upon the wheel-rim of the conical flange B^3 is of great advantage in connection with the operation of the plow, inasmuch 55 as it affords a continuous or annular surface or receptacle upon or in which the earth may fall in passing from the mold-board. Said flange will, in practice, preferably be polished 60 upon its inner surface, so that the material deposited thereon will have no tendency to adhere to its surface and will readily slide inwardly upon the rim as the wheel revolves.

The plow, instead of being located at the 65 outer side of the wheel, may be placed at the inner side thereof and beneath the wagon, this construction being shown in Fig. 7. In

this case the conical flange B^3 will be located upon the same side of the wheel as that from which the material is discharged; but the operation of the said flange and the buckets will obviously be the same as before set forth.

The form of the buckets and the adjacent parts of the wheel when the construction last 70 mentioned is used is shown in Fig. 8. The bucket shown in Fig. 8 does not differ from those shown in the other figures, except that the inclination is reversed of the transversely-arranged spout C^5 for conveying the material 75 laterally into the wagon-body as it is discharged from the buckets. The location of the plow at the outer side of the wheel, as shown in Figs. 1, 2, and 4, is obviously much to be preferred, for the reason that in this construction the wagon is located on the furrow-side of the plow, so that the supporting-wheels thereof rest and travel upon a surface from which material has been removed, and for the reason also that the rim of the wheel B , as 80 clearly shown in Fig. 4, is thereby brought below the natural surface of the ground at the landside of the plow, and consequently in a position most favorable for receiving the material lifted by the said plow.

95 Instead of the plow herein shown, which is obviously adapted more particularly for use in cases in which it is desired to remove soil in excavating, a scraper adapted to take up and throw laterally upon the wheel-rim the 100 material to be loaded, may obviously be used—as, for instance, in loading loose earth or sand or objects—such as loose stones—scattered upon the surface of the ground.

In order to provide means for distributing 105 in the wagon-body the material delivered at one side of it by the loading device as above set forth, devices are herein shown which are constructed as follows: Hinged at its upper edge to the inner surface of the side of the 110 wagon-body beneath the deflecting-plate A^3 is a leaf or board, M , adapted to oscillate freely about its pivotal axis and constructed to normally hang in a vertical position and flat against the said side of the wagon-body. To 115 the lower or free edge of said leaf or board M is attached a rope, cord, or chain, M' , which is trained over suitable guide-pulleys, $m m'$, at the side of the wagon-body opposite to that upon which the said board is hung and is passed 120 partially around and connected with a freely-rotatable pulley or drum, M^2 , mounted upon the outer vertical surface of the wagon-body adjacent to the supporting-wheel B , as shown in Figs. 2 and 4. The said drum is provided 125 with a radially-extending arm or projection, m^2 , located in position to be encountered by one or more stops or projections, m^3 , upon the wheel B' , the parts being arranged in such manner that when the said stops m^3 encounter 130 the arm m^2 the drum will be rotated and the rope or cord M' thereby wound thereon so as to draw the lower edge of the board M toward the middle of the wagon-body. The said

board will thus, in the forward movement of the wagon, be successively thrown upwardly and given an oscillatory movement calculated to throw toward the middle of the wagon-body 5 and to distribute evenly therein the material falling upon said board from the buckets C.

A wagon constructed generally as above described obviously cannot be readily constructed so that it may be tilted for the purpose of discharging the material therefrom; and in order to provide a simple and easily-operated device for this purpose means are herein provided as follows: The bottom of the wagon-body is formed by two broad parts or 15 boards, N N, which are hinged at their outer edges to the lower edges of the sides of the body, and are preferably arranged to stand, when closed, in an inwardly and downwardly inclined position and to meet at their free edges at the 20 middle line of the body. This inclined position of the parts N N is not essential, inasmuch as the device may be operated in the same manner when the said parts are made somewhat narrower, so that they may close to form a 25 horizontal bottom to the body; but the construction shown is preferred, inasmuch as it gives a greater capacity in the body and enables the said parts to be opened with a less angular movement than would otherwise be 30 necessary. The hinged parts N N are held in their closed position by means of chains O, connected with the said parts N N near the inner or free edges of the latter, and attached at their upper ends to a horizontal bar, P, which 35 is arranged longitudinally over the body and is journaled to rotate about a longitudinal axis. The said chains are connected with the bar P at points laterally distant from its axis of rotation, the parts being so arranged that 40 when the bar is turned so as to bring the points of attachment of the chains downward the chains will be lowered and the parts N N of the bottom permitted to fall, and when turned to bring the said points of attachment 45 upward the said parts N N will be drawn upwardly and closed.

As herein shown and preferably constructed, the bar P is made of wood and relatively wide and thin in cross-sectional form, and is 50 pivoted to rotate about an axis lying at or near one of its edges, the means of pivotally supporting the said bar herein shown consisting of an iron bar, P', which is bolted to the edge of the wooden bar and is provided at its 55 ends with journals p', supported in bearings p upon the cross-piece G at the rear end of the body, and a cross-piece, A⁴, at the forward end thereof.

The chains O are attached by any suitable 60 means to the bar P at its edge remote from the iron bar P'.

By the construction above set forth, a bar may be obtained capable of supporting the parts of the bottom when the wagon is loaded, 65 and which combines a minimum of size and weight with a maximum of strength, for the reasons that the strain upon the bar is trifling

at times when the parts N N are open or are being moved and the bar is in an inclined or horizontal position, and that when the said 70 parts are closed and the wagon is loaded the said bar will stand with its flat sides vertical, and will therefore be in a position to most effectually resist the weight of the load.

As a convenient means of actuating the bar 75 P, the latter is provided with a laterally-projecting arm, P², which may be grasped by the hand in rotating the bar. Said arm is herein shown as connected with the journal p' of the bar at the forward end of the latter, and is 80 arranged to rest horizontally upon the cross-piece A⁴ when the bar P is in position for holding the wagon-bottom closed.

In order to lock the bar in the position last mentioned, a lever, Q, is pivoted upon the forward part of the frame in position to rest transversely across the outer end of the arm P² when the latter is horizontal. The pivotal point of the said lever Q is located close to the arm P², so that the said arm may be held 90 from movement by relatively little pressure upon the free end of the lever, and a simple hook or catch, q, is preferably used for holding the free end of the said lever from upward movement.

The parts N N, forming the bottom of the wagon, are preferably so arranged that their free ends nearly reach the ground when the said parts are allowed to fall, the chains O serving to hold the said sides from outward movement past a vertical position. By this means the material discharged from the wagon is held from spreading laterally upon the lower parts of the wheels B and B'.

The wagon may be provided with the usual 105 tail-board; but, as herein shown, the tail-board is absent, whereby the passage of the wagon when emptied over the pile of material deposited beneath it is greatly facilitated.

A wheel constructed generally as above set forth may obviously be used in connection with a two-wheeled cart or with a wagon constructed otherwise than as shown; and my invention, as it relates to features of construction in the wheel, is not therefore limited to 115 the particular construction shown in the other parts of the wagon, excepting as set forth in the appended specific claims.

I claim as my invention—

1. A loading device for wagons, consisting, 120 essentially, of a wheel having a broad flat rim and a series of buckets located upon the inner surface of the rim, each bucket of the series having its mouth toward the rear of the wagon when said bucket is at the bottom of the wheel 125 or adjacent to the ground, substantially as and for the purpose set forth.

2. A loading device for wagons, consisting 130 of a wheel provided about its periphery with a series of buckets having their inner walls or those nearest to the center of the wheel inclined inwardly toward the center of the wheel and toward the mouths of the buckets, whereby the material will be discharged by gravity

from the said buckets when the latter are at the top of the wheel, substantially as described.

3. The combination, with the wagon-body, of a loading device comprising a wheel located 5 at the side of the wagon-body and having about its periphery a series of receptacles or buckets, said wheel being provided with deflecting plates or chutes C^5 , inclined inwardly toward the axis of the wheel and the wagon-body, whereby material discharged from the buckets will be carried laterally into the wagon-body, substantially as described.

4. A wagon-loading device comprising a wheel having a wide rim provided with a series 15 of buckets secured to the rim, said rim being provided at one edge with a conical flange located exterior to the side walls of the buckets, substantially as and for the purpose set forth.

20 5. A wagon-loading device comprising a wheel having a wide rim provided with a series of buckets, said rim having a conical flange at one of its edges and a plow or equivalent device located at the side of the wheel adjacent 25 to the said conical flange for lifting and delivering material upon the rim, substantially as described.

6. A wheel for wagon-loaders of the character herein described, the rim of which is formed 30 of two or more rings of thin or sheet metal riveted together, one of said rings being provided at one edge of the rim with a conical flange, substantially as and for the purpose set forth.

35 7. A wagon-loading device comprising a wheel having a wide rim and a series of buckets secured to the inner surface of the rim, and having a series of inclined flanges or ribs, as C^7 , upon the inner surface of the rim between the buckets, constructed to carry inwardly material delivered to the outer portion of the rim, substantially as described.

8. A wheel for wagon-loaders provided with a relatively thin and wide rim with a series 45 of buckets secured to the rim and with spokes for supporting the said rim, having their outer ends secured in the rim and located adjacent to the walls of the buckets, substantially as and for the purpose set forth.

50 9. A wheel for wagon-loaders provided with a wide rim, a series of buckets secured to the rim, and spokes for supporting the rim secured in the latter at points adjacent to the walls of the buckets, the portions of said 55 buckets remote from the rim being attached to and supported by the said spokes, substantially as described.

10. The combination, with a wheel, B, having a wide metal rim formed of two or more 60 thicknesses of metal, of buckets C, formed of sheet metal, and angle-irons C^6 , for securing the side walls of the buckets to the said rim, said angle-irons being secured to the rim by rivets passing through and holding together 65 the several thicknesses of metal composing the latter, substantially as described.

11. The combination, in the wheel B, hav-

ing a metal rim and sheet-metal buckets, of angle-irons C^6 , for securing the side walls of the said buckets to the said rim, said angle-irons being provided with sockets for spokes, and spokes for supporting the said rim having their outer ends inserted in said sockets, substantially as described. 70

12. The combination, with the wheel B, having a metal rim provided with flanges B^3 and B^4 , sheet-metal buckets comprising walls C' and C^2 , secured to the rim by means of angle-irons C^6 and walls C^2 , riveted to the flange B^4 , substantially as described. 75 80

13. The combination, with the wheel B, having a wide rim, of a series of buckets, C, having walls C' , C^2 , and C^3 , secured to the rim, the wall C' being inwardly-inclined from the edge of the rim, substantially as and for the 85 purpose set forth.

14. A wheel, for the purpose set forth, comprising in its structure a wide rim provided with a conical flange, B^3 , at one edge and a vertical flange, B^4 , at its opposite edge, and a 90 series of buckets, C, each of which comprises a side wall, C' , located at the side of the wheel adjacent to the conical flange and inclined inwardly from the edge of the rim, and side walls, C^2 , opposite the side walls, C' , and adjacent to 95 and in the same plane with the flange B^4 , a rear wall, C^3 , and an inner wall, C^4 , inclined inwardly and toward the mouth of the buckets, substantially as described.

15. The combination, with a wheel having a 100 wide rim, said rim being provided with a conical flange, B^3 , of a bucket, C, having a side wall, C' , and an angle-iron, C^6 , for securing the said side wall of the bucket to the rim, said angle-iron being extended at its end adjacent 105 to the said flange B^3 outwardly over the surface of the latter, substantially as and for the purpose set forth.

16. A wheel provided about its periphery with a series of buckets, C, and with laterally-inclined curved chutes C^5 , connected with the inner side walls of the buckets, substantially as and for the purpose set forth. 110

17. A wheel provided about its periphery with a series of buckets, C, and with chutes C^5 , 115 made integral with the inner side walls of the buckets, substantially as and for the purpose set forth.

18. A wheel having a wide rim, B^3 , and spokes supporting the rim and provided about 120 its periphery with buckets C, and provided also with chutes C^5 , connected at one of their edges with the buckets and supported at their opposite edges by the said spokes, substantially as and for the purpose set forth. 125

19. The combination, with the wagon-body, of a wheel having about its periphery a series of buckets, C, and provided with chutes C^5 inclined inwardly toward the wheel-axis and wagon-body, said wagon-body being provided 130 with a deflecting plate or shield, A^3 , substantially as and for the purpose set forth.

20. The combination, with a wagon, and a wheel located at one side of the wagon-body

and provided about its periphery with a series of receptacles or buckets, of a plow located at one side of the wheel, and a frame for connecting the plow with the wagon, said frame being pivoted at its rear end to the wagon-frame and extended downwardly and forwardly with its forward end in position for the attachment of the plow-beam, and means for adjustably sustaining the forward end of the frame from the wagon, substantially as and for the purpose set forth.

21. The combination, with a wagon, and a wheel having a series of receptacles or buckets about its periphery, of a downwardly and forwardly inclined frame, F, pivotally connected at its rear end with the wagon-body, means for adjustably sustaining the front end of the said frame, and a plow having its beam attached to the lower forward end of the said frame F, said plow being adjustably attached at its rear portion to the said frame, substantially as and for the purpose set forth.

22. The combination, with a wagon, and a wheel provided with buckets, as C, of a downwardly and forwardly inclined frame, F, pivotally connected at its rear end with the wagon and adjustably supported at its front end from the latter, a plow, E, having a beam, E', connected with the frame F and provided with arms E², a hand-lever, F², pivoted upon the frame F and connected with the said arms E², and a notched segment and detent or equivalent device for holding the hand-lever in a desired position whereby the rear end of the plow may be adjusted vertically with reference to the frame, substantially as described.

23. The combination, with a wagon-body, and a wheel provided with buckets, as C, of a downwardly and forwardly inclined frame, F, pivotally connected at its rear end with the wagon and adjustably supported from its front end from the latter, a plow, E, having a beam, E', connected with the forward end of the frame F and provided with arms E², a hand lever, F², pivoted upon the said frame, and a rock-shaft, F³, mounted upon the frame and provided with arms connected with the said arms E² and with the lever F², and a notched segment and detent or equivalent device for holding the said hand-lever in a desired position, substantially as described.

24. The combination, with the pivoted frame F and plow E, of the hand-lever H', provided with the arm H², a chain, H, connecting the said arm H² with the free end of the frame, and a notched segment and detent or equivalent device for holding the said hand-lever in a desired position, substantially as and for the purpose set forth.

25. The combination, with a wagon-body, and a loading device delivering material at one side of the said body, of a board or leaf hinged to the side of the body beneath the point at which the material is delivered thereto, and means operated by one of the wheels of the wagon for giving an oscillatory movement to the said board or leaf, whereby ma-

terial falling upon the said board or leaf will be distributed in the wagon-body, substantially as described.

26. The combination, with the wagon-body, and a loading device delivering material at one side of the said body, of a board or leaf hinged to the side of the body beneath the point at which the material is discharged therein, a drum or pulley located upon the side of the wagon-body adjacent to one of the wheels thereof and provided with a radially-extending arm or projection, a rope or cord attached to the drum and connected with the said board or leaf, and a projection or stop upon the wheel constructed to engage the arm or projection upon the drum, whereby the latter will be rotated and the said board or leaf given an oscillatory movement in the forward movement of the wagon, substantially as described.

27. The combination, with a wagon-body, and a board or leaf, M, of a drum, M², mounted upon the side of the wagon-body adjacent to one of the wheels thereof and provided with a radially-extending arm or projection, a rope or cord, M', attached to the drum and to the said leaf or board, suitable guide-pulleys for the rope or cord, and a stop upon the wheel located in position to engage said arm or projection, substantially as and for the purpose set forth.

28. A dumping device for a wagon, consisting of two parts or boards, N N, hinged at their edges to the sides of the wagon-body, a longitudinally-arranged bar made of considerably greater width than thickness, and pivoted over the center of the wagon-body so as to rotate about an axis lying at or near one of its edges, and chains connecting the free ends of the boards composing the bottom of the wagon-body with the edge of said bar remote from its pivotal axis, said bar being so arranged that when its said edge is turned downwardly the said bottom will be opened and when the said edge is turned upwardly said bottom will be closed, whereby, when the bottom is closed, the strain caused by the weight of the material thereon will come edge-wise upon the beam, substantially as described.

29. The combination, with the wagon-body, and boards N N, of the bar P, chains connecting points upon the said bar remote from its axis with the said boards, said beam being provided at one end with an arm, P², a lever, Q, pivoted upon the wagon-body and constructed to engage the free end of said arm, and means for temporarily holding the free end of said lever, substantially as and for the purpose set forth.

In testimony that I claim the foregoing as my own I affix my signature in presence of two witnesses.

ALEXANDER M. WOOLFOLK.
